MACHINE FOR PAVING STREETS

Heinrich Bührmann, Meerbusch, near Düsseldorf, Germany

Application November 30, 1937, Serial No. 177,382
In Germany December 3, 1936

6 Claims. (CL. 94—47)

This invention relates to a device for laying paving stones, particularly artificial stones.

Paving by hand requires relatively much time, is quite expensive and fails to produce the desirable or necessary uniformity in laying. Furthermore, it is difficult to find pavers for larger jobs.

The invention eliminates these troubles by successively arranging on a frame extending over the entire width of the street or road, or over a portion thereof, and being movable in the longitudinal direction of the street to be paved, a device for placing the embedding mass on the bottom ballasting or metal layer and planing the mass, a device for laying the stones into the embedding mass in a regular and accurate manner, and a device for pressing or ramming the stones. Paving is thus divided into three phases, and the corresponding operations can be carried out either simultaneously or successively by the new device.

By way of example, the invention is illustrated in the accompanying drawings, in which Figure 1 is a vertical section showing the device in elevation as seen from the street; Fig. 2 is a plan view of Fig. 1; Fig. 3 is a cross section of the ramming device; Fig. 4, a partial top view thereof; Fig. 5, a section on the line 5—5, of Fig. 1; Fig. 6, a section on the line 6—6, of Fig. 3; and Fig. 7, a perspective view of the pavement showing the three working phases.

Referring to the drawings, the device comprises a frame movable in the longitudinal direction of the street to be paved and having two side frames 1 provided with the wheels 2 and connected by the cross struts 3. The frame 1, 2, 3 preferably extends over the entire width of the street and can be moved along the street on rails 23. The device for putting on the embedding mass comprises a funnel-shaped receptacle 4 having smooth walls on all sides and movable in a transverse direction on the wheels 7. The hopper or receptacle 4 is moved along the rails 26 by hand, or by any suitable means (not shown). The receptacle 4 contains the embedding material 24, such as cement mortar, bitumen mortar, sand, etc., and during operation discharges its contents in a transverse direction upon the bed or road metal 5. A bar 6 adjustable as to height serves for roughly leveling the embedding material 24 after it is delivered from the receptacle 4. The bar 6 may be adjustable as to height in any suitable manner. As shown, it is mounted on a pair of substantially vertical supports 6a which are slidably connected to the

frame 4a of the receptacle 4. Any suitable means (not shown) for maintaining the supports 6a in an adjusted position may be used. The hopper 4 may be connected with a mixing machine (not shown) which forms no part of my invention, for the mass. The receptacle 4 can be moved on exchangeable rails 26 whose top side corresponds to the cross section of the street so as to adapt the mass 24 to the sectional profile of the street.

For supplying the stones 8 a manually or mechanically operated belt conveyor 27 or a slide (not shown) is employed which may be provided with bottom rolls. Near the conveyor 27 a narrow platform 28 extends from one side frame 1 to the other for the accommodation of the workers. Beside the platform 28 a frame 9 is disposed and provided with several rows of staggered compartments or cells 10 which are open above and below and into which the stones 8 fit with some play. The upper and lower side of the frame 9 is adapted to the profile of the street to be paved. The frame 9 is suspended from wire ropes 11 which can be raised and lowered and are guided over sheaves 12 on the side frames 25 1. The drive for the sheaves 12 consists for instance of bevel gears 13 which are turned by means of a crank, lever, etc. to raise or lower the frame 9. When the frame 9 is lowered, the stones 8 are inserted in the cells 10, the walls 30 of which correspond to the joints, and are thus placed in final position on the road metal 5. After the filling of the cells 10 the frame 9 is raised, moved farther along the road bed and lowered again onto the ballasting 5 so as to be 35 in direct connection with the previously laid stones.

The device for pressing or ramming the stones comprises for instance a plurality of wooden ramming planks 14 which by means of longitudinal 40 irons 29 and transverse reinforcements 30 can be combined to form a plate which at its ends is held by carrying plates 15. The carrying plates 15 are guided in a vertical frame 16 on the side portions 1 of the movable frame and 45 with their rolls 17 move on a slide 18 possessing inclined cam surfaces 21 and moved forward and backward by a screw spindle 19 and a driving wheel 20. During forward motion of the slide 18 the rolls 17 of the carrying plates 15 engage 50 the inclined cam surfaces 21 of the slide 18, whereby the plates 15 and thus the pressure members 14 are lifted, whilst rapid return motion of the spindle 19 causes the rolls 17 to slide off from the inclined cam surfaces 21 so quickly that 55

the pressure members 14 drop suddenly and strike the rows of stones. Motion of the ramming planks can be effected also by spindles. According to the nature of the stones and embedding material to be used, single planks and stampers or suitable combinations of both may be employed.

The device functions as follows:

- 10 After the embedding material 24 has been placed on the ballasting 5 by the receptacle 4 moving on the frame 1, 2, 3 in the transverse direction of the street and the member 6 has preparatorily planed the material the frame 1, 2, 3 is moved in the longitudinal direction of the street to the extent of the width of the paving section to be produced while simultaneously an adjustable planer 22 extending over the entire width of the street completes the planing of the embedding mass 24. The frame 9 is then lowered to rest on the mass 24, and the artificial stones 8 disposed on the belt conveyor 27 are inserted in the cells 16 of the frame 9. In the meantime, embedding material is spread over the adjacent portion of the bottom ballasting and preparatorily planed by the member 6. When filled with stones the frame 9 is raised again and the frame 1, 2, 3 moved forward to the extent of the width of the section to be paved, so that the ramming device 14 is disposed above the stones 8 placed in the embedding mass 24. During motion of the frame 1, 2, 3 the preparatorily planed section is finished again by the planer 22, so that the frame 9 will be located above the newly finished section and the previously laid rows of stones are rammed or pressed into the embedding material 24 by the pressure member 14 and the stones thus finally set, as indicated in Fig. 7. During the ramming operation fresh stones are placed in the lowered cell frame 9 and in the connecting section of the street embedding material is spread out and subjected to preliminary planing. The frame 1, 2, 3 is then advanced again the width of a section, and the three phases of the paving process can thus be 45 continued and carried out by means of the mechanical equipment.

I claim:

1. A device for paving a street or the like with paving stones or the like, comprising a frame 50 extending over at least a part of the width of said street, means mounting said frame for movement over said street longitudinally thereof, a hopper carried by said frame for applying embedding material to said street, means mounting said hopper for back and forth movement transversely of said frame and street, means carried by said hopper and operative to preparatorily plane said material in a transverse direction as said hopper is moved across said frame to deliver embedding material to said street, a guide frame 55 comprising at least one transverse row of stone guiding open cells carried by said frame rearwardly of said hopper, means for lowering and raising said guide frame to and from a position on said embedding material, said guide frame comprising means for regularly and accurately laying a batch of paving stones in said embedding material when said guide frame is in the lowered position, and means carried by said frame rearwardly of said guide frame for simultaneously tamping all of said batch of laid stones into said embedding material.

2. A device for paving a street of the like with paving stones or the like, comprising a frame 60 extending over at least a part of the width of

said street, means mounting said frame for movement over said street longitudinally thereof, a hopper carried by said frame for applying embedding material to said street, a guide frame comprising at least one transverse row of stone 5 guiding open cells carried by said frame rearwardly of said hopper, means for lowering and raising said guide frame to and from a position on said embedding material, said guide frame comprising means for regularly and accurately 10 laying a batch of paving stones in said embedding material when said guide frame is in the lowered position, means carried by said frame rearwardly of said guide frame for simultaneously tamping all of said batch of laid stones into 15 said embedding material.

3. A device for paving a street or the like with paving stones or the like, comprising a frame extending over at least a part of the width of said street, means mounting said frame for movement 20 over said street longitudinally thereof, a hopper carried by said frame for applying embedding material to said street, means mounting said hopper for back and forth movement transversely of said frame and street, means carried by 25 said hopper and operative to preparatorily plane said material in a transverse direction as said hopper is moved across said frame to deliver embedding material to said street, a guide frame comprising at least one transverse row of stone 30 guiding open cells carried by said frame rearwardly of said hopper, means for lowering and raising said guide frame to and from a position on said embedding material, said guide frame comprising means for regularly and accurately 35 laying paving stones in said embedding material when said guide frame is in the lowered position, and means carried by said frame rearwardly of said guide frame for tamping said laid stones into said embedding material, a finishing planer 40 for said embedding material extending transversely of said street, said finishing planer being carried by said frame between said hopper and said guide frame.

4. A device for paving a street or the like with paving stones or the like, comprising a frame 45 extending over at least a part of the width of said street, means mounting said frame for movement over said street longitudinally thereof, a hopper carried by said frame for applying embedding material to said street, means mounting said hopper for back and forth movement transversely of said frame and street, means carried by said hopper and operative to preparatorily plane said material in a transverse direction as said 50 hopper is moved across said frame to deliver embedding material to said street, a guide frame comprising at least one transverse row of stone 55 guiding open cells carried by said frame rearwardly of said hopper, means for lowering and raising said guide frame to and from a position on said embedding material, said guide frame comprising means for regularly and accurately laying a batch of paving stones in said embedding 60 material when said guide frame is in the lowered position, and means carried by said frame rearwardly of said guide frame for simultaneously tamping all of said batch of laid stones into said embedding material, said tamping means including a tamping member, cams carried by said 65 frame and engageable with said member for raising and dropping the same to tamp said stones, and means for actuating said cams.

5. A device for paving a street or the like with paving stones or the like, comprising a frame 70

extending over at least a part of the width of said street, means mounting said frame for movement over said street longitudinally thereof, a hopper carried by said frame for applying embedding material to said street, means mounting said hopper for back and forth movement transversely of said frame and street, means carried by said hopper and operative to preparatorily plane said material in a transverse direction as said hopper is moved across said frame to deliver embedding material to said street, a guide frame comprising at least one transverse row of stone guiding open cells carried by said frame rearwardly of said hopper, means for lowering and raising said guide frame to and from a position on said embedding material, said guide frame comprising means for regularly and accurately laying a batch of paving stones in said embedding material when said guide frame is in the lowered position, means carried by said frame rearwardly of said guide frame for simultaneously tamping all of said batch of laid stones into said embedding material, a finishing planer for said embedding material extending transversely of said street, said finishing planer being carried by said frame between said hopper and said guide frame, and means carried by said frame for delivering stones to the vicinity of said guide frame.

6. A device for paving a street or the like with paving stones or the like, comprising a frame ex-

tending over at least a part of the width of said street, means mounting said frame for movement over said street longitudinally thereof, a hopper carried by said frame for applying embedding material to said street, means mounting said hopper for back and forth movement transversely of said frame and street, means carried by said hopper and operative to preparatorily plane said material in a transverse direction as said hopper is moved across said frame to deliver embedding material to said street, a guide frame comprising at least one transverse row of stone guiding open cells carried by said frame rearwardly of said hopper, means for lowering and raising said guide frame to and from a position on said embedding material, said guide frame comprising means for regularly and accurately laying paving stones in said embedding material when said guide frame is in the lowered position, means carried by said frame rearwardly of said guide frame for tamping said laid stones into said embedding material, a finishing planer for said embedding material extending transversely of said street, said finishing planer being carried by said frame between said hopper and said guide frame, an operator's platform on said frame adjacent said guide frame, and means carried by said frame for delivering stones to the vicinity of said platform.
